(57) **CLAIM**

The ornamental design for a loudspeaker front face, as shown and described.

DESCRIPTION

FIG. 1 is a perspective view of a loudspeaker front face showing the new design;

FIG. 2 is a front elevational view thereof;

FIG. 3 is an enlarged partial perspective view of the waveguide portion thereof;

FIG. 4 is a perspective cross-sectional view thereof, taken along line A-A of FIG. 2;

FIG. 5 is a cross-sectional view of the waveguide portion thereof, taken along line A-A of FIG. 2;

FIG. 6 is a perspective cross-sectional view thereof, taken along line B-B of FIG. 2;

FIG. 7 is an enlarged partial perspective cross-sectional view of the waveguide portion thereof, taken along line B-B of FIG. 2; and,

FIG. 8 is a cross-sectional view of the waveguide portion thereof, taken along line B-B of FIG. 2.

The broken lines and unshaded areas form no part of the claimed design. The shading illustrated in the figures is provided merely to represent the contours of the design and is not intended to be illustrative of, for example, texture, material, gloss, translucence, transparency, or surface decoration.
